REACTIVE ELECTRON DISCHARGE CIRCUITS

James F. Wilcox, Scotia, and Edwin W. Kenefake,
Schenectady, N. Y., assignors to General Electric Company, a corporation of New York

Application July 11, 1942, Serial No. 450,498

7 Claims. (Cl. 179—171.5)

Our invention relates to electron discharge circuits, and more particularly to such circuits arranged to transmit adjustable amounts of reactive current.

Electron discharge devices have been arranged with their discharge paths across a source of alternating potential and with their control electrodes so excited from the alternating potential that a reactive current flows in the discharge path. It is usually desired that the amount of reactive current flowing in such a discharge path vary linearly with respect to changes in the average bias potential of the control electrode. Such devices are commonly connected across a tuned circuit to adjust, according to the potential on the control electrode, the resonant frequency of the tuned circuit.

Such resonant circuits, whose operating frequency may be readily adjusted, are used to produce frequency modulated carrier waves, the adjustably tuned circuit being the frequency controlling circuit of an oscillator. It has been found that one of the advantages of frequency modulation is attained when the amount of frequency shift of the carrier wave is greater than the highest frequency of the modulating signal. For example, an ordinary audio signal may contain components up to about 5000 cycles making it desirable to shift the frequency of the carrier wave about 25,000 cycles from its mean frequency in either direction.

Adjustably tuned circuits, as described above, are capable of varying their resonant frequency an amount in the order of 5 or 6% of the carrier frequency, as they are usually constructed. It is therefore evident that, if the carrier frequency is less than about twenty times the highest frequency component of the signal to be transmitted, the usual type of adjustable frequency tuned circuit is not capable of shifting the frequency of the carrier wave sufficiently to give the large frequency swing desired. For example, with a carrier wave of 50 kilocycles, as frequently used for carrier current transmission, a 3% swing in either direction would be about 1500 cycles in either direction. If the highest frequency component of the signal to be transmitted were only 3,000 cycles, with such a low ratio of the highest signal frequency to the carrier frequency swing, a low signal to noise ratio results.

It is an object of our invention to provide a new and improved adjustable reactance discharge device whose reactance is variable linearly with respect to a control voltage over a wider range than has heretofore been attained.

It is a corollary object of our invention to provide such a reactance device which is especially useful at low carrier wave frequencies for producing a larger frequency swing for the purpose of producing frequency modulations.

The features of our invention which we believe to be novel are set forth with particularity in the appended claims. Our invention itself, both as to its organization and manner of operation, together with further objects and advantages thereof may best be understood by reference to the following description taken in connection with the accompanying drawing in which Fig. 1 illustrates one embodiment of our invention and Fig. 2 shows certain characteristics of the apparatus of Fig. 1.

In the apparatus of Fig. 1 signals from a microphone 10 modulate the resonant frequency of a circuit including a discharge device 11, the resonant circuit being maintained in oscillation by a discharge device 12, and such frequency modulated oscillations being amplified through a power amplifier 13 and impressed on a power line 14 through a coupling condenser 15. The cathode 16 of the oscillating discharge device 12 is grounded, the control electrode 17 thereof is connected through a grid leak resistance 18 to ground and is coupled through a coupling condenser 19 to one terminal 28 of a tuned circuit comprising that part of an inductance 20 between an intermediate tap 22 and terminal 20, and a variable condenser 21 connected between tap 22 and terminal 28. The intermediate tap 22 is connected to the anode 23 of the device 12, and is coupled through a suitable coupling condenser 24 to the amplifier 13.

Discharge current for the device 12 is supplied from the positive terminal of a source 25 of operating potential, whose negative terminal 40 is grounded through an intermediate tap 26 of the inductance 20 between the tap 22 and terminal 28 of the inductance. The tap 26 is bypassed to ground by a bypassing condenser 27 for high frequency currents.

So connected, with the tap 26 and the cathode 16 of device 12 at fixed potentials, and opposite terminals 22 and 28 of the tuned circuit including inductance 20 and condenser 21 coupled respectively to the anode 23 and control electrode 17 of the device 12, continuous oscillations are maintained in the tuned circuit, at a frequency determined by the resonant frequency of the tuned circuit.

The discharge device 11, which controls the resonant frequency of the tuned circuit including

the inductance 20 and condenser 21, has an anode 36 connected to that terminal of the inductance 20 opposite the terminal 28. The cathode 31 of device 11 is connected to ground through a biasing resistance 32 in parallel with the bypassing condenser 33. The first, or control, electrode 34 is connected to ground through a pair of resistances 35 and 36, connected in series, and through the microphone 10. The second or screen electrode 37 of the device 11 is connected to cathode 31 through a suitable bypassing condenser 38, and is also connected through a resistance 39 to the positive terminal of the source 25.

The control electrode 34 of the device 11 is excited with a voltage which is out of phase with the voltage across the tuned circuit 20, 21, by a condenser 40 connected between control electrode 34 and tap 22 of the inductance 20. A point between the resistances 35 and 36 is connected to terminal 28 of the tuned circuit through a suitable bypassing condenser 41, whereby the voltage across the tuned circuit including condenser 21 and that part of inductance 20 between taps 22 and 28 is impressed across the condenser 40 and resistance 35 in series. Consequently, a current flows through the condenser 40 and resistance 35 which is leading in phase with respect to the voltage across the condenser 21. This leading current through the resistance 35 produces a leading voltage thereacross, which in turn appears on the control electrode 34 of device 11 and causes a leading current to flow in the discharge path of the device 11.

By reason of the fact that the phase shifting network 35-40 is connected across the entire tuned circuit including condenser 21 and a portion of inductance 20, and the fact that an intermediate tap 28 of that tuned circuit is maintained at a fixed potential, the alternating potential impressed on the control electrode 34 of the device 11 with respect to cathode 31 may be made to differ in phase by exactly 90° from the alternating potential across condenser 21. That is, by suitably proportioning the condenser 40 and resistance 35, the voltage between the control electrode 34 of device 11 and intermediate tap 28 of inductance 20 may be made to be exactly 90° out of phase with the alternating potential between tap 22 and terminal 28 of inductance 20. The proper adjustment is attained when the voltage across resistance 35 has a component in phase with the voltage between taps 22 and 28 of inductance 20 equal to the alternating potential between taps 26 and 28 of inductance 20.

By reason of the autotransformer action of the inductance 20, a larger high frequency potential appears on the anode 30 of the reactance device 11 than on the anode 23 of the oscillating discharge device 12. This higher alternating potential on the anode 30 of the device 11 produces a large reactive current flow through the impedance presented by the discharge path of the device 11, so that the magnitude of the reactance presented by device 11 to the anode circuit of device 12 is smaller than if the anode 30 were connected directly to tap 22 and anode 23 of device 12. Therefore, device 11 appears as a larger capacity at the anode of device 12 than if the two anodes 23 and 30 were connected directly. The microphone 10 is so connected as to vary the average potential on the control electrode 34 at signal frequency, thereby adjusting in accordance with the signal the amount of reactive current flowing through the discharge path of device 11.

A suitable bypassing condenser 42 is connected

in shunt to the microphone 10, so that, in connection with the resistance 36, a low pass filter is formed to prevent the appearance across the microphone 10 of alternating potential of the frequency of the carrier wave generated by device 12. The reactance of condenser 42 should be substantial at the frequency of signals from microphone 10 to avoid undesirable attenuation thereof.

In Fig. 2 a curve 50 illustrates the relation between the instantaneous signal potential from microphone 10 and the resulting frequency deviation of the carrier wave generated by the device 12. In this figure the instantaneous signal potentials in volts are plotted as abscissae, and the resulting frequency deviations in kilocycles as ordinates. At the frequency deviation indicated as zero, the carrier frequency was actually 38.5 kilocycles and the instantaneous signal potential 3.87 volts. By a change of about 2 volts on either side of this operating condition, the frequency of the carrier wave was changed linearly about 5 kilocycles in either direction. The total linear frequency change thus produced was more than 11 percent of the average carrier frequency.

When an autotransformer arrangement, such as that in Fig. 1 including the inductance 20, is utilized to produce a wide linear frequency swing in response to a modulating potential, it is desirable that amplitude modulation of the frequency modulated carrier wave be minimized. If an alternating potential be applied to the control electrode 34 of device 11 which has a component in phase with the alternating potential between taps 22 and 28 of the inductance 20, a regenerative or degenerative effect is produced upon the tuned oscillator circuit through the action of current flowing through the anode 30 controlled in accordance with the alternating potential on the control electrode 34. This regenerative or degenerative action results in the production of amplitude modulations of the oscillating potential maintained in the tuned circuit 20, 21 by the oscillating discharge device 12.

In order to minimize said amplitude modulation in the presence of the wide frequency swing attainable with our frequency modulation arrangement, it is desirable to use the phase shifting network including condensers 40 and 41 and resistance 35, which is effective to impress an alternating potential on the control electrode 34 with respect to cathode 31 of device 11 which is exactly 90° out of phase with the alternating potential across the tuned circuit including condenser 21 and that portion of inductance 20 between the taps 22 and 28.

Our invention may be utilized to modulate the frequency of any carrier wave, such as for a radio transmitter, over a very wide frequency band. It may, in fact, be utilized to take a large reactive current from any source of alternating potential, where such a reactive current is desired.

While we have shown and described a particular embodiment of our invention, it will be obvious to those skilled in the art that changes and modifications may be made without departing from our invention in its broader aspects, and we, therefore, aim in the appended claims to cover all such changes and modifications as fall within the true spirit and scope of our invention.

What we claim as new and desire to secure by Letters Patent of the United States is:

1. In combination, an oscillator including an electron discharge device having an anode and a control electrode connected to opposite terminals

of a resonant circuit to excite oscillations therein, said resonant circuit including a winding, a second electron discharge device having an anode, a cathode and a control electrode, a second winding connected in series with said winding and comprising therewith an autotransformer, said autotransformer having its end terminals connected between the anode and cathode of said second discharge device, means for supplying to the control electrode of said second discharge device oscillations having such phase relations to oscillations on the anode of said second discharge device that a reactive current flows between the anode and cathode thereof and through said autotransformer, and means for supplying a variable unidirectional potential to the control electrode of said second electron discharge device to vary said reactive current and thereby to control the tuning of said resonant circuit and the frequency of oscillations excited therein by said first discharge device, said autotransformer increasing the reactive effect of said second electron discharge device upon said resonant circuit and extending the range of said frequency variations.

2. In combination, a source of alternating potential, means for taking from said source an adjustable reactive current, said means comprising an electron discharge device having an anode, a cathode, and a control electrode so connected across said source that a reactive current flows between said anode and cathode and the impedance of said device between said anode and cathode simulates a reactance, means comprising a step-up autotransformer interposed between said source and said device, said autotransformer having its end terminals connected between said anode and cathode and an intermediate portion thereof connected across said source thereby to increase the reactive effect of said device on said source, and means to modulate the current between said anode and cathode in accordance with a varying electromotive force thereby to modulate the reactive current drawn by said device from said source in accordance with the variations of said electromotive force.

3. In combination, a source of alternating potential, a reactance device comprising an inductance and arranged to take a reactive current from said source, means for impressing potential from said source across a portion of said inductance, an electron discharge device having an anode, a cathode and a control electrode, said anode and cathode being connected to electrically spaced points of said inductance including appreciably more of said inductance than said portion thereof, and phase shifting means for impressing alternating potentials from said source between said control electrode and said cathode in displaced time-phase relation with respect to the alternating potential between said anode and cathode.

4. In combination, a source of alternating potential, a reactance device comprising an inductance and arranged to take a reactive current from said source, means for impressing potential from said source across a portion of said inductance, an electron discharge device having an anode, a cathode and a control electrode, said anode and cathode being connected across a second portion of said inductance greater than and including said first portion, and means comprising a reactance and a resistance connected serially across said first portion of said inductance for impressing between said control electrode and

5 said cathode an alternating potential derived from said source of potential and displaced in time-phase relation with respect thereto, said means comprising a connection between said control electrode and a point between said reactance and resistance.

5. In combination, an oscillator including an electron discharge device having an anode and a control electrode connected to opposite terminals of a resonant circuit to excite oscillations therein, said resonant circuit including a winding, a second electron discharge device having an anode, a cathode and a control electrode, a second winding connected in series with said winding and comprising therewith an autotransformer, said autotransformer having its end terminals connected between the anode and cathode of said second discharge device, and phase shifting means connected to derive from said resonant circuit and apply to the control electrode of said second electron discharge device an alternating voltage in substantially quadrature relation with respect to the voltage of said resonant circuit thereby to effect the flow of a reactive current through said 20 second electron discharge device and said autotransformer and to minimize any tendency of said second discharge device to modulate the intensity of oscillations to said resonant circuit.

6. A variable frequency oscillator having a 30 tuned circuit of which an electrically intermediate point is maintained at a fixed potential, said tuned circuit including a condenser connected in shunt to an inductance, an additional inductance connected in series with said first inductance, an 35 electron discharge device having an anode, a cathode and control electrode, means for impressing alternating potential from said tuned circuit between said control electrode and cathode in displaced time-phase relation with respect to the phase of the alternating potential of said source, means for connecting said anode and cathode to the electrically remote terminals of said inductance, whereby the auto-transformer action of 40 said inductance increases the reactive effect of said discharge device and a component of said alternating potential between said control electrode and cathode in phase with the alternating potential of said tuned circuit tends to produce amplitude modulation of said alternating potential on said tuned circuit, and means for increasing the time phase relation of alternating potential between said control electrode and cathode with respect to the time phase of the alternating potential across said tuned circuit substantially to a quarter wave of said alternating potential to minimize such amplitude modulation.

7. A variable frequency oscillation generator 50 comprising an inductance, a condenser connected across a portion of said inductance and forming with said portion a tuned circuit, means for maintaining an electrically intermediate point of said portion of said inductance at a fixed potential, means for maintaining oscillations in said 55 tuned circuit, an electron discharge device having an anode, a cathode and a control electrode, said anode being connected to a first terminal of said inductance electrically spaced from said tuned portion and said cathode being maintained at a second fixed potential and connected to a second terminal of said inductance and means for impressing an alternating potential between said control electrode and cathode in displaced time-phase relation with respect to the phase of 60 alternating potential across said tuned circuit

comprising a resistance and reactance serially connected in shunt to said tuned circuit, said control electrode being connected between said reactance and resistance, said reactance at the resonant frequency of said tuned circuit being so related to said resistance that the alternating potential impressed thereby between said control

5 electrode and cathode is substantially in quarter phase relation with the alternating potential across said tuned circuit whereby modulation of the amplitude of oscillations in said tuned circuit is minimized.
